United States Patent Office

Des. 213,786
Patented Apr. 8, 1969

213,786

PET PAD

Harold J. Pohl, 612 W. 2nd St., Washington, Mo. 63090

Filed Mar. 29, 1968, Ser. No. 11,190

Term of patent 14 years

Int. Cl. D30—99

U.S. Cl. D30—41

FIG. 1

FIG. 2

FIG. 1 is a perspective view of a pet pad, showing my new design, and

FIG. 2 is a similar view taken from the opposite direction from that of FIG. 1.

The pets are shown in broken lines for illustrative purposes only.

I claim:

The ornamental design for a pet pad, as shown and described.

UNITED STATES PATENT OFFICE
CERTIFICATE OF CORRECTION

Design No. 213,786

April 8, 1969

Harold J. Pohl

It is certified that error appears in the above identified patent and that said Letters Patent are hereby corrected as shown below:

In the heading to the drawing and printed specification, line 3, "Harold J. Pohl, 612 W. 2nd St., Washington, Mo. 63090" should read -- Harold J. Pohl, Washington, Mo., assignor to Kellwood Company, St. Louis, Mo., a corporation of Delaware --.

Signed and sealed this 14th day of April 1970.
